ELECTRIC INCANDESCENT LAMP AND
SIMILAR DEVICEHeinrich Asmussen, Berlin-Steglitz, Germany,
assignor to General Electric Company, a corporation of New YorkApplication May 28, 1934, Serial No. 728,007
In Germany June 2, 1933

5 Claims. (CL. 176—32)

My invention relates to electric incandescent lamps and similar devices comprising a bulb having an electric energy translation element such as a filament sealed therein and a base mounted on said bulb. More particularly my invention relates to the bases for such devices and still more particularly to so-called mechanical bases in which the usual cement which unites the base to the glass bulb is eliminated.

10. Mechanical bases proposed heretofore have been objectionable because they necessitated a comparatively complicated structure of the base shell or bulb. One of the objects of the present invention is to provide a base which is firmly secured 15 to the neck of the bulb without the use of cement and is of comparatively simple design.

According to my invention, the neck of the bulb is provided with longitudinal engagement means, preferably one or more grooves, which are engaged 20 by corresponding engagement means in the base shell, preferably indentations therein, thereby preventing the said base shell from rotating on the said bulb neck. The base shell is held on the bulb neck solely by means of a leading-in 25 wire having high tensile strength, said wire being stretched tightly between the usual stem press of the lamp and the end of the base to which said wire is secured.

In the ordinary incandescent lamp, the copper leading-in wires are approximately .30 to .35 mm. in diameter. Such wires are comparatively soft and have low tensile strength, so that they were never stretched tightly heretofore because of the danger of breakage. However, this danger 35 is obviated if a lead wire, for example of copper, having a comparatively large diameter, is used, or if a metal or alloy wire of standard diameter but having a high tensile strength, is used. For instance, a copper wire of .50 mm. diameter or over 40 may be used without fear of breakage, or leads of the usual diameter, i. e., .30 mm. may be used when made of, for example, beryllium-bronze, phosphor-bronze or steel. Such wires, when tightly stretched between the stem press and the 45 end of the base, hold the said base firmly on the neck of the bulb and prevent any movement thereof longitudinally of the bulb.

For a further understanding of the invention, reference may be had to the appended drawing 50 in which Fig. 1 is an elevation, partly in section, of an incandescent lamp having a base structure comprising my invention; Fig. 2 is an elevation of the base at right angles to Fig. 1; and Figs. 3 and 4 are respective similar views of a modified base structure.

Referring to Fig. 1, the lamp comprises a bulb 10 having a filament 11 sealed therein and supported on wires 12 the ends of which are sealed in the end of an arbor 13 which extends from the press portion 14 of a stem tube 15. The cylindrical neck 16 of the bulb is provided with a pair of longitudinal grooves 17. A base comprising a screw threaded shell 18, insulation 19 and an eyelet 20 surrounds said neck portion of said bulb. The shell 18 has a pair of indentations 21 therein 10 which engage with the grooves 17 and prevent rotation of said shell with respect to the bulb. A pair of leading-in wires 22—23 having portions thereof sealed in the stem press 14 are connected at their inner ends to the ends of the filament 11. 15 The leading-in wire 22 is bent over the neck of the bulb, placed in one of the grooves 17 and bent over the edge of the shell 18, the end thereof being soldered in the corresponding indentation 21. The said leading-in wire 22 may be of the usual 20 diameter of .30 to .35 mm., but the leading-in wire 23 is of greater diameter, preferably greater than .50 mm., for example, .60 to .80 mm. Said leading-in wire 23 is secured to the end of the base, preferably by solder 24 which forms an end 25 contact, and is stretched tightly between the said end of the base and the stem press 14, thereby securely holding the said base on the neck of the bulb.

In the species shown in Figs. 3 and 4 the neck 30 of the bulb is provided with screw threads 25 formed therein. The base consists of a cap comprising a metal shell or ring 26, insulation 27 and an eyelet 28. The shell 26 has a pair of indentations 29 therein which engage with longitudinal 35 grooves 30 in the bulb neck to prevent relative rotation of the said shell and bulb neck. The lead wire 23 is soldered at 31 to the eyelet 28 in the same manner as in Figs. 1 and 2.

The invention is of course also applicable to 40 other sealed devices such as radio tubes, arc lamps and electrical discharge devices.

What I claim as new and desire to secure by Letters Patent of the United States is:

1. An electrical device comprising a bulb having a neck portion and a base comprising a metal shell surrounding said bulb neck and an end contact, said bulb neck and base shell having interlocking engagement means therein for preventing relative rotation therebetween, and a leading-in wire having a portion thereof sealed in a portion of said bulb and an end thereof secured fixedly to said base end contact, said leading-in wire being tightly stretched between said bulb and base and constituting the sole means for 55

holding said base firmly on said bulb neck against longitudinal displacement.

2. An electrical device comprising a bulb having a neck portion and a base comprising a metal shell surrounding said bulb neck and an end contact, said bulb neck having a longitudinal groove therein and said base shell having an indentation therein engaging with said groove for preventing relative rotation between said base and bulb, and a leading-in wire having a portion thereof sealed in a portion of said bulb and an end thereof secured fixedly to said base end contact, said leading-in wire being tightly stretched between said bulb and said base and constituting the sole means for holding said base firmly on said bulb neck against longitudinal displacement.

3. An electrical device comprising a bulb having a neck portion and a base comprising an end contact and a metal shell surrounding said bulb neck and having screw threads formed therein, said bulb neck having a longitudinal groove therein and said base shell having an indentation therein engaging with said groove for preventing relative rotation between said base and bulb, and a leading-in wire having a portion thereof sealed in a portion of said bulb and an end thereof secured fixedly to said base end contact, said leading-in wire being tightly stretched between said bulb and said base and constituting the sole means for holding said base firmly on said bulb neck against longitudinal displacement.

4. An electrical device comprising a glass bulb

having a neck portion having screw threads formed therein and a base comprising an end terminal contact and a metal shell constituting a second terminal contact surrounding a portion of said bulb neck, said bulb neck having a longitudinal groove therein and said base shell having an indentation therein engaging with said groove for preventing relative rotation between said base and bulb, a leading-in wire electrically connected to said base shell and a second leading-in wire having a portion thereof sealed in a portion of said bulb and an end thereof secured fixedly to said base end contact, said leading-in wire being tightly stretched between said bulb and said base and constituting the sole means for holding said base firmly on said bulb neck against longitudinal displacement.

5. An electrical device comprising a bulb having a neck portion and a base comprising a metal shell surrounding said bulb neck and a single end contact, said bulb neck and base shell having interlocking engagement means therein for preventing relative rotation therebetween, and a leading-in wire having a portion thereof sealed in a portion of said bulb and an end thereof secured fixedly to said base end contact, said leading-in wire being tightly stretched between said bulb and base and constituting the sole means for holding said base firmly on said bulb neck against longitudinal displacement.

HEINRICH ASMUSSEN.
